SHELF ASSEMBLY FOR VENDING MACHINES
Harry R. Payne, Chattanooga, Tenn., assignor to Cavalier Corporation, Chattanooga, Tenn., a corporation of Tennessee

Filed Mar. 14, 1963, Ser. No. 265,116
3 Claims. (Cl. 193—40)

This invention relates to shelf assemblies for vending machines and more particularly to such assemblies for vending machines of the type in which a plurality of sloping shelves are arranged one above the other in the vending machine with articles disposed on the shelves to roll under the force of gravity to a dispensing position for each shelf.

More particularly still, this invention relates to shelf assemblies which are provided with resilient means engaging the base of the articles on the shelf to prevent binding of the base as the article rolls towards dispensing position so that the article will roll evenly and uniformly on the shelf and not turn axially with respect to the direction of movement.

In vending machines of the type shown in the Hsu et al. Patent No. 2,875,922 of March 3, 1959, a plurality of vertically disposed shelves are employed with each shelf holding a plurality of generally cylindrical articles, hereinafter referred to as bottles. These shelves slope toward the dispensing position so that the bottles can roll down the shelves to dispensing position. It has been found that the bases of the bottles in engagement with the upstanding rear edge of the shelf tend to bind or stick as the bottles roll down the shelf so that the neck portion of the bottle advances with respect to its base and the bottle becomes canted on the shelf. This may interfere with the proper movement of the remainder of the bottles toward the dispensing position and may also interfere with the proper operation of the release mechanism at the dispensing position.

Others have attempted to provide shelf assemblies assuring the even rolling of the bottles down the shelves as in U.S. Patent No. 3,008,783 of November 14, 1961. These shelf assemblies are, however, usually expensive to make which is undesirable in the highly competitive vending machine industry.

I have now found that bottles disposed on a sloping shelf in a vending machine can be made to roll evenly down the shelf by preventing binding of the base of the bottle against the upstanding rear edge of the shelf through the use of a resilient member placing pressure on trailing edge of the base of the bottle. This force prevents the base of the bottle from binding against the upstanding edge of the shelf and the bottle will roll uniformly and evenly down the shelf.

It is therefore the object of the present invention to provide a novel shelf assembly for a vending machine provided with resilient means engaging the trailing edge of the bases of the bottles on the shelf to prevent the bases of the bottles from binding against the upstanding edge of the shelf so that the bottles will roll uniformly and evenly and in parallel relationship down the shelf to dispensing position.

The present invention is capable of various mechanical embodiments. A preferred embodiment of the present concept is shown in the accompanying drawing and is described hereinafter to illustrate the invention. This illustrative embodiment should in no way be construed as defining or limiting the invention.

In the accompanying drawings, in which like reference characters indicate like parts, FIG. 1 is a perspective view of a preferred embodiment of a shelf in accordance with the present invention showing a preferred way of applying

2

ing pressure to the trailing edges of the bases of the bottles on the shelf;

FIG. 2 is a side view of the embodiment of FIG. 1;

FIG. 3 is a cross sectional view on the line 3—3 of 5 the embodiment of FIG. 1 at right angles to the long axis thereof; and

FIG. 4 is an enlarged detail of the right end of the embodiment of FIG. 1.

Referring now to the several figures, a platform or 10 vending station is generally indicated at 10 to receive a bottle at a time from the associated shelf 11. The bottle is vended from platform 10 by any suitable and conventional means, not shown. Platform 10 is supported by and within the housing of the vending machine, also not 15 shown. Platform 10 is provided with a downwardly and outwardly extending flange 12 receiving down turned flange 13 of shelf 11. Shelf 11 is provided with a flat bottom 14 and with an upstanding rear edge or wall 15 disposed at approximately right angles to bottom 14. A 20 hook 16 is suitably secured to edge 15 as by spot welding at 17 and the hook portion 18 thereof engages in slot 19 in platform 10 to lock shelf 11 securely in position with respect to platform 10.

A tab 20 is turned down from end 21 of base 14 and 25 is received in a slot 22 in support member 23 which is carried by the vending machine housing, not shown. Support 23 is disposed above platform 10 in the vending machine housing to provide shelf 11 with the desired 30 downward slope so that the bottles will roll freely down shelf 11 to platform 10.

Shelf 11 is provided with a longitudinal planar front 35 wall portion 24 upturned with respect to bottom 14 terminating in turned edge 25, edge 25 being disposed beneath the necks of the bottles disposed on shelf 11. As seen in FIG. 3, the taper of the bottles 26 resting on bottom 14 causes the bases 27 of the bottles 26 to lie at an angle of a degree or two from wall 15 as shown at 28. The lower portion only of the edge of bottom 27 would therefore engage rear wall 15.

However, as pointed out above, I have found that even 40 this limited engagement of the edge of bottom 27 with wall 15 is sufficient to retard the movement of the bases of bottles 26 so that the neck portion 29 of bottles 26 can roll more freely and may advance ahead of bases

45 27 so that bottles 26 may become undesirably canted on shelf 11. Binding of bases 27 of bottles 26 is overcome by applying a continuing force to the trailing edges of bases 27. To obtain this force a resilient member 30 substantially coextensive with wall 15 is secured at 50 one end thereto as by spot welds 31. A hole is bored in the other end of member 30 at 32 to receive one end of spring 33. The other end of spring 33 is hooked into hole 34 in bottom 14. Spring 34 urges member 30 away from wall 15.

When the vending machine is loaded for the vending 55 of bottles, a plurality of bottles are disposed on shelf 11 each in engagement with the next and with their long axes substantially parallel to ends 13 and 21 of shelf 11. The bottles and their contents are relatively heavy and when 60 the bases 27 of the bottles are forced against member 30, member 30 will move toward wall 15 expanding spring 33. Only the trailing edge of base 27 of each bottle is engaged by member 30 so that a force is constantly exerted on the trailing edge of the base of each bottle as 65 the bottles move down shelf 11 toward platform 10. This force applied to the trailing edge of each bottle prevents the base of each bottle from binding against member 30 and the bottles roll to vending position on platform 10 uniformly and evenly, maintaining their long axes approximately parallel to ends 21 and 13 of shelf 11. The necks of the bottles are prevented from rolling

70

ahead of the bases of the bottles and the bottles are prevented from rolling out of the desired alignment.

It should now be apparent that the present invention in every way satisfies the objective discussed above.

Changes in or modifications to the illustrative embodiment of this invention as described above may now be suggested to those skilled in the art without departing from the present inventive concept. Reference should therefore be had to the appended claims to determine the scope of this invention.

What is claimed is:

1. In a shelf assembly for vending machines having a bottle vending station, and for supporting and feeding bottles to the station, an elongated planar shelf bottom of substantially uniform width having opposed ends mounted in an inclined position adjacent to said station with one end lower than the other end, a rear wall extending substantially the length of said bottom and extending upwardly at approximately right angles thereto, a substantially planar front wall extending the length of said bottom opposite said rear wall and extending upwardly

with respect to said bottom and underlying the necks of the bottles on said bottom, the bases of the bottles on said bottom being adjacent said rear wall and resilient means mounted on and converging downwardly with said rear wall applying pressure to the trailing edge of the bases of each of the bottles.

2. In an assembly as described in claim 1, said resilient means comprising strip means having opposed ends and substantially coextensive with said rear wall and secured 10 at one end to said wall adjacent said station and spring means urging the other end of said strip means away from said wall.
3. In an assembly as described in claim 2, said spring means being secured to said strip means and to said bottom.
